Atty.

UNITED STATES PATENT OFFICE.

EDWIN A. NEIBERGER, OF ELMHURST, ILLINOIS.

SCREEN-WIRE BINDER.

Application filed September 20, 1926. Serial No. 136,499.

This invention relates to a novel method of attaching a screen to the frame therefor together with a novel instrumentality for accomplishing this purpose.

5 The method of securing screen to the frame therefor has been to preliminarily fasten the edges of the screen to the frame by means of any suitable instrumentality such as staples or tacks or by means of a strip of wood insertable in a groove provided therefor in the frame portion of the screen, the edge of the screen being confined underneath the inserted strip of wood. When the screen was secured in place it was then the practice to apply a 10 thin strip of wood or other suitable material over the edge of the screen to conceal the irregularities resulting from the operation of attaching the screen to the frame.

The operation in the past has been somewhat difficult to perform, requiring usually the work of skilled mechanics and in addition thereto has taken an unduly long time due to the number of steps in the operation. The length of time employed and the material 15 used increased materially the cost of the usual house screen.

One of the principal objects of the present invention is the provision of an improved method whereby a screen may be secured to the frame therefor more quickly and economically than heretofore.

Another object of the invention is the avoiding of the undesirable features connected with the screen industry as pointed out in a preliminary paragraph.

Still another object is the provision of a novel instrumentality by means of which a screen may be secured to the frame and the edge thereof concealed from view in a single operation.

A further object is the provision of a strip for simultaneously securing a screen to the frame thereof, and concealing the edge of the screen.

A still further object is the provision of a strip of a durable nature which may be employed for securing a screen to a frame therefor, and which may be employed indefinitely without injury thereto.

In accomplishing the objects above pointed out a strip is provided having a plurality of downwardly projecting points and a plurality of circular apertures at spaced intervals thereon. The screen is laid out on the frame, the points extended through the mesh of the

screen and into the wooden portion of the frame, said strip being secured in place by the employment of a plurality of wood screws, each one of said screws extending through one of the circular apertures provided in the strip.

60 The invention is capable of several modifications, which modifications together with additional features and objects of the invention will be pointed out with some particularity in the following description and may become apparent from a consideration of the drawings which are furnished in connection therewith, in which drawings,

Figure 1 is a fragmentary view of a screen 70 showing one form which the invention may take;

Figure 2 is a sectional view taken on the line 2—2 on Figure 1 looking in the direction of the arrows;

Figure 3 is another form which the invention may take;

Figure 4 is a sectional view taken on the line 4—4 of Figure 3;

Figure 5 is a view showing another form 80 which the strip may take and

Figure 6 is still another form in which the strip may be manufactured in accordance with the invention.

Reference may now be had to the accompanying drawings, particularly to Figures 1 and 2, which embodiment of the invention will be described first, but this order of selection is not meant to indicate that this is the preferred form of the invention.

90 In Figures 1 and 2 numeral 10 refers to the upper portion of the frame and numeral 11 the side portion thereof, a screen 12 being supported thereon by means of strips 13 and 14 which are held in place by means of screws 95 15—15. The strips 13 and 14 are each provided with an upraised marginal portion, this marginal portion on the strip 14 being plainly shown in Figure 2 and being designated by the reference character 16.

100 Depending downwardly from the strip, particularly from one edge of the inside edge of the margin portion 16 are triangular projections or tangs 17 (Figure 2). The triangular projections 17 are formed by cutting two sides of the triangle from the strip preferably contiguous with the upraised marginal portion 16. The cutting of the strip in this manner leaves a triangular opening therein designated by the reference characters 18—18, so 110

that the triangular tang 17 struck therefrom is articulated as a continuation of the marginal upraised portion 16 to enable the penetration thereof without bending. This arrangement affords the articulation of the tang 17 incident to impressing the upraised marginal portion 16 in the strip 14, thereby precluding the necessity of weakening the line of jointure to the tang with the body of the strip owing to the initial bending thereof.

There is a novel method employed in assembling the screen, but this method will not be described until after the other forms which the strip may take and which are shown in Figures 3 to 6 inclusive have been described.

In the embodiment shown in Figures 3 and 4 the screen frame is designated by the reference characters 10' and 11' and the screen by the reference character 12'. The strip there-
20 in represented and designated by the reference character 20 is flat with the exception of downwardly extending projections 21 and 22 (Figure 4), said downward projections being formed from the strip by incising the
25 same in the manner indicated by the dotted lines in Figure 3. In this way the projections 21 will all be on the left hand side of the strip and the projections 22 on the right hand side of the strip. The same construction is ob-
30 tained of course whether the strip 20 is on the side of the frame or at the top or bottom there-
35 of. The reference characters 21 and 22 are employed to designate the projections on the side members simply for purposes of clear-
in Figure 4.

Where the flat form of strip is employed a corner cap 23 is secured at the intersection 40 thereof at the corner, said corner cap being secured to the frame by means of screws 24-24. Where the mitred form shown in Figure 1 is employed it is of course unnecessary to employ a corner cap.

In the form shown in Figure 5, projections similar to those shown in Figures 3 and 4 are employed but an upraised marginal portion is employed, designated 14' and being of similar shape as the marginal portion designated 50 14 in Figures 1 and 2. The bottom as shown in Figure 6 is flat and is provided with the normal circular aperture for accommodating screws for securing the strip to the frame, but the projections thereon are formed on the 55 margin of the strip instead of in the center thereof. The teeth in Figure 6 are designated by the reference character 25.

Each one of the strips shown in Figures 5 and 6 may be employed in exactly the same 60 manner as shown in Figures 1 and 3, since the strips readily lend themselves to this form of use without the necessity of any modification whatsoever.

In assembling the screen, the screen portion 12 is laid out over the frame and the

strips are brought into place. Before securing the strips to the frame the downward projections thereon are caused to engage the edge of the screen and a gentle pressure is applied thereto to stretch the screen upon the frame sufficiently to get a taut effect. The screws 15 are then inserted in the apertures provided therefor and quickly driven home by means of any usual form of screw driver.

When the four strips on a screen have been 75 secured to the frame the finished screen is ready for use and if at any time after the completion thereof the screen portion becomes damaged or worn all that it is necessary to do is to remove the screws and apply 80 a new portion of screen. The screws can readily be returned into the same holes in the frame, thus avoiding unnecessary wear to this member.

The strip is preferably made of metal but 85 other material may be used. Where the strip is made of metal it is obvious that the downwardly extending projections could readily be cut from the material itself in the manner shown in the drawings. However, I contemplate the provision of separate projections, no limitation being necessary as to the manner in which the projections are made. The invention contemplates the use of other material besides metal in which case the projections could very nicely be made of metal and embedded in the material of the strip in any suitable manner. For example, a strip might be made of hard rubber and a species 90 of padded projection employed, with the head portion of the projection member embedded in the rubber before the vulcanization thereof.

This is only an example as of course there are any number of materials which could be 105 employed in accomplishing the invention. The only requirements are that the projection be downward from the under side of the binder strip and be of such a character that it will accomplish the purpose. It is within 110 the province of the present invention to make the projections sufficiently long and sharp so that they can be embedded in the frame of the screen without the necessity of employing screws or other fastening means.

Among the advantages of the binder strip which is the subject matter of the present invention is the fact that it is a time and trouble saver since with its use the screen wire can be attached more easily and more 120 quickly than by old methods. It also serves as a stretcher, enabling the workman to get the wire properly in place with less effort than in the old way.

It takes the place of a molding and makes 125 the use of a separate molding unnecessary and hence saves this item of expense in screen making. It fastens the wire more securely than staples or tacks which have been employed to a large extent ~~ere now~~.

In addition, the simplicity and durability of the binder strip makes it easy to operate and hence it may become a practical convenience to an unskilled workman at the same 5 time lasting indefinitely even in the hands of the unskilled.

In the description of the invention it has been necessary to refer to the binder strip somewhat in detail but it is not meant to limit 10 the invention by such details, the scope of the invention being defined by the appended claim.

I claim:

The combination with a frame member, of foraminous material disposed thereon, strips 15 disposed on said frame member to overlap said foraminous material, an upraised marginal portion impressed in said strips, tangs struck in said strips to constitute a continuation of said marginal portion to engage said 20 foraminous material, and fasteners for detachably securing said strips to said frame members.

EDWIN A. NEIBERGER.
